(57) **CLAIM**

The ornamental design for a display screen for communications terminal with graphical user interface, as shown and described.

DESCRIPTION

A portion of the disclosure of this patent document contains material to which a claim for copyright and trademark is made. The copyright and trademark owner has no objection to the reproduction of the patent document or the patent disclosure, as it appears in the U.S. Patent Office records, but reserves all other copyright and trademark rights whatsoever.

The sole FIGURE is a front view of a display screen for communications terminal with graphical user interface. The broken lines in the drawings illustrate a display screen of communications terminal and portions of the graphical user interface that forms no part of the claimed design.
